Attorney

UNITED STATES PATENT OFFICE.

WILMER H. YERKES, OF PITTSBURGH, PENNSYLVANIA.

IRONING-MACHINE.

1,362,980.

Specification of Letters Patent. Patented Dec. 21, 1920.

Application filed March 24, 1920. Serial No. 363,347.

To all whom it may concern:

Be it known that I, WILMER H. YERKES, a citizen of the United States, residing at Pittsburgh, in the county of Allegheny and State of Pennsylvania, have invented certain new and useful Improvements in Ironing-Machines, of which the following is a specification.

This invention relates to ironing machines, and more particularly to a machine specially adapted to ironing garments and large pieces of work.

One of the main objects of the invention is to provide a machine of the character stated of simple construction and operation including a stationary ironing member and means for ironing the articles over the same. Another object is to provide ironing means specially adapted for ironing skirts and similar articles. A further object is to provide means for ironing and supporting large articles in such manner as to avoid necessity of folding and consequent creasing of the same. Further objects will appear from the detailed description.

In the drawings:

Figure 1 is a front view of the machine.

Fig. 2 is a side view.

Fig. 3 is a top plan view with the rack omitted.

Fig. 4 is a side view, with parts omitted, taken from the side opposite to Fig. 3.

Fig. 5 is an end view of the spider.

Fig. 6 is an end view of the drum, the main iron and associated parts being shown in section.

Fig. 7 is a diagram of the means for adjusting the iron.

The machine includes a main frame 1 supporting a top plate 2 on which are secured aligned standards 3 in which a shaft 4 is rotatably mounted. A bracket 5 is secured on inner standard 3 and co-operates with a bracket 6 at the other end of plate 2 to support a table 7 adjustably connected to the brackets by bolts 8 passing through the table and through slots 9 in the upper ends of the bracket.

The inner edge of table 7 is beveled to conform substantially to the curvature of a drum 10 secured on shaft 4. As will be noted more clearly from Fig. 4, the frame of the machine adjacent to the outer end of the drum is open thus permitting ready insertion and removal of articles, such as skirts, onto and from the drum longitudi-

nally thereof. A brace 11 of concave cross-section is secured to the inner standard 3 and extends beneath the drum and about the outer end thereof to support shaft 4 and hold the same against sagging. For ironing unusually long articles, I provide a spider 12 which is adapted to be secured by a set screw 13 on the end of shaft 4 which projects beyond the outer end of the drum for this purpose. This spider carries a plurality of circularly arranged rods 14 which serve to support large articles, such as sheets and similar articles, during ironing of the same thus avoiding the necessity of folding and consequent creasing of such articles.

A worm gear 15 is secured on shaft 4 and meshes with a worm 16 on a counter shaft 17 rotatably supported by bracket arms 18 projecting from the inner standard 3. A groove pulley 19 is secured on the counter shaft and is connected by a cord 20 to a pulley 21 secured on the armature shaft of an electric motor 22 mounted on a bracket 23 secured to frame 1. This provides means whereby the drum may be rotated during the ironing operation.

The drum 10 co-operates with an ironing member 24. This member includes a relatively thick ironing plate 25 which extends about the inner portion of the drum, and is concaved to conform substantially to the curvature of the drum. A hood 26 is mounted on the outer side of plate 25 and contains suitable burners 27 for heating said plate. A supplemental ironing plate 28 is slidably mounted in plate 25, a suitable housing 29 being provided over the opening 30 in which this supplemental plate operates. An operating rod 31 is connected at one end, by ball and socket connections, to plate 28. The other end of this rod is connected to an eccentric 32 secured on a counter shaft 33 rotatably mounted in a standard 34 positioned adjacent the back of plate 25, a bevel pinion 35 is secured on the forward end of shaft 33 and meshes with a bevel gear 36 loose on shaft 4, this bevel gear being provided with a clutch element 37 which co-operates with a companion element 38 feathered on the shaft and adjusted by a clutch lever 39 pivoted to a finger 40 projecting from the outer standard 3. By means of clutch lever 39 the plate 28 may be reciprocated at will during operation of the machine. This supplemental plate 28 is very useful in ironing skirts and similar articles.

having plaits at the waist or hip portions, as this member reciprocating longitudinally of the drum serves to effectually smooth and press the plaits and prevents spreading or 5 wrinkling of the same such as would occur if this supplemental reciprocating member were not provided.

Two links 41 are pivoted at their outer ends to an upright 42 secured to the corner 10 of plate 2 adjacent the outer end of the drum, and the inner ends of these links are pivoted at 41^a to the outer end of hood 26. Similar links 43 are pivoted to inner standard 3 and to the inner end of the hood. The 15 lower link of each pair is connected by a rod 44 to one arm of a bell crank 45 the outer arm of which is connected by pin and slot connections to a rod 46 slideable in bearings 46^a. One end of rod 46 is loosely connected 20 to an arm 47 carried by an adjusting rod 48 workably mounted in bearings 49 and provided at one end with a lever 50 secured thereon. As will be clear from Fig. 7, by 25 turning the lever in proper directions the ironing plate 25 and associated parts may be readily adjusted toward and away from the drum as required to suit the thickness of the goods being ironed or for introducing a skirt over the drum.

30 A vertical sleeve 51 is secured to standard 34 and coöperates with a similar sleeve 52 carried by upright 42 to support two vertical poles 53. These poles carry substantially triangular frames 54 which support 35 spaced horizontal bars 55 which form a rack for supporting the articles being ironed. As this rack is positioned above the machine I effect a material saving in space

compared to the usual racks or arms which project from the sides of ironing machines 40 of the type now in common use.

As will be understood, there may be changes made in details of construction and arrangement of parts of the invention without departing from the field and scope of 45 the same, and I intend to include all such variations, as fall within the scope of the appended claims, in this application in which a preferred form only of my invention is disclosed.

What I claim is:—

1. In an ironing machine, the combination of a single horizontal drum supported at both ends; the outer support of said drum comprising an arm extending below and adjacent to the whole length of said drum and secured to the inner support, and means mounted on and revolving with the shaft of said drum for supporting horizontally goods to be ironed of greater width than 55 the length of said drum.

2. In an ironing machine, the combination of a single horizontal drum of uniform diameter supported at both ends; the outer support of said drum comprising an arm extending below and adjacent to the whole length of said drum and secured to the inner support; a spider mounted on the extension of the shaft of said drum protruding beyond the outside support, said spider having 65 a plurality of horizontal apertures circumferentially disposed to correspond to the periphery of said drum and a plurality of bars insertible and securable in said apertures.

In testimony whereof I affix my signature. 75
WILMER H. YERKES.
